UNITED STATES PATENT OFFICE.

E. A. TURPIN, OF NEW YORK, N. Y.

IMPROVEMENT IN BREECH-LOADING ORDNANCE.

Specification forming part of Letters Patent No. 36,325, dated August 26, 1862.

To all whom it may concern:

Be it known that I, E. A. TURPIN, of the city, county, and State of New York, have invented a certain new and useful Improvement in Breech-Loading Cannon; and I do hereby declare the following to be a full, clear, and exact description of the same, reference being had to the accompanying drawings, making part of this specification, in which—

Figure 1 is a horizontal axial section of my improved cannon. Fig. 2 is a vertical axial section of the same:

Similar letters of reference indicate corresponding parts in both figures.

The nature of my invention consists in closing the breech of a piece of ordnance or other fire-arm by means of an axial plug inserted from the rear, fitting at its front end a seat in the breech, and secured by a tapering pin or wedge, which passes transversely through the breech and plug, as will be hereinafter explained.

Though especially designed for cannon, my invention is also applicable to small-arms.

To enable others skilled in the art to which the invention pertains to make and use the same, I will proceed to describe its construction and operation as applied to cannon.

A represents the main body of the gun, which is bored completely through from end to end, and formed at back with an enlarged cylindrical chamber to receive an axial plug, B, which is inserted from the rear. The general form of the plug B is cylindrical; but it is formed with a conical end, which fits a seat at the front end of the enlarged chamber, as seen at b'.

aa are two coincident slots in the sides of the breech-chamber.

b b represent one or more slots extending transversely through the plug B, which slots correspond in position with the slots aa, but may be of greater length.

C is a tapering wedge or key, which passes completely through the slots aa and b, bearing against the rear ends of the former and the front end of the latter, so as to force and hold the plug B firmly within its chamber and against its seat b'.

T T represent the trunnions, and V the vent.

To load the gun the key C and plug B are

withdrawn. The charge is then inserted from the rear through the enlarged chamber and into the smaller part of the bore. The plug B is then replaced and the key C driven in so as to force the end of the plug firmly home against its seat. The gun is then ready for firing.

It will be apparent that the expansion of the gun, caused by its repeated discharge, will not impair the tightness of the joint in the rear of the charge, because every time the plug is inserted it is forced tightly home against its seat by the action of the key. The sides of the plug and chamber are made of cylindrical form to permit the plug to be thus forced up against the seat, and also to permit the plug to be turned upon its axis, by which means its end may be ground upon the seat whenever needful to make it fit tightly.

The slots aa and b are so placed as to afford bearing for the key against the back end of the former and the front end of the latter, as before stated; but the slots aa extend a sufficient distance forward and the slot b a sufficient distance backward to provide for the setting up of the plug as its end and the seat wear away. The front of the slot b is made convex, as shown, to facilitate the inserting of the key and to cause its inclined edge to bear against the center of the plug.

Having thus described my invention, what I claim therein as new, and desire to secure by Letters Patent, is—

Closing the breech of a piece of ordnance or other form of fire-arm by means of an axial plug having a smooth cylindrical surface and a conical end fitting a corresponding seat in the breech of the gun, the said plug being adapted to be turned upon its seat and held firmly in contact therewith by means of a tapering key or wedge, C, passing transversely through the breech and plug, all as herein shown and described, for the purposes set forth.

The above specification of my improvements in breech-loading ordnance signed this 12th day of February, 1862.

E. A. TURPIN.
